UNITED STATES PATENT OFFICE.

CHARLES J. VAN DEPOELE, OF LYNN, MASSACHUSETTS.

RECIPROCATING ELECTRIC ENGINE.

SPECIFICATION forming part of Letters Patent No. 431,493, dated July 1, 1890.

Application filed April 3, 1890. Serial No. 346,396. (No model.)

To all whom it may concern:

Be it known that I, CHARLES J. VAN DEPOELE, a citizen of the United States, residing at Lynn, in the county of Essex and State of Massachusetts, have invented certain new and useful Improvements in Reciprocating Electric Engines, of which the following is a description, reference being had to the accompanying drawings, and to the letters of reference marked thereon.

My invention relates to improvements in electro-magnetic reciprocating engines, and comprises improvements in the structure thereof whereby they are better adapted to meet the various conditions of actual service and of varying circumstances.

The means for producing the current by which my said engines are operated and the circuits and connections existing between the source of current and the motor-coils is not herein shown, and the same may be substantially such as is shown, described, and claimed in Letters Patent Nos. 400,809 and 401,231, granted to me, respectively, April 2 and April 9, 1889, or as shown in subsequent patents.

The present invention relates, principally, to means whereby the forward or backward stroke may be caused to preponderate in force, and to means whereby the plunger or magnetic piston may be always properly positioned at starting. Where the engine is to be employed for actuating a drill boring a vertical hole, the weight of the parts will naturally bring the piston to a downward position.

In machines employed in horizontal positions—as, for example, in undercutting coal—the plunger can stop anywhere; but a machine embodying the present improvements will always have its plunger in the center of the working-coils when at rest.

The invention also comprises other details of construction and arrangement, as will be fully set forth in the following description, and referred to in the appended claims.

In the accompanying drawings, Figure 1 is a view in elevation, partly in section, showing the construction and arrangement of an electro-magnetic reciprocating engine embodying my invention. Fig. 2 is a view similar to Fig. 1, except that certain parts of the

machine are differently disposed. Fig. 3 is a detail view, partly in section, showing the magnetic piston and parts directly connected therewith. Fig. 4 is a view in elevation showing a complete machine and a form of support therefor. Fig. 5 is a sectional view on the line 5 5 of Fig. 4, with parts broken away to show friction-joint. Figs. 6 and 7 are detail views, on an enlarged scale, illustrating the tool-rotating mechanism seen in Fig. 1.

As indicated in Figs. 1, 2, and 5, A B are the motor-coils. C is an exterior iron casing or shell inclosing said coils, and D D' are iron heads secured in the extremities of the shell and inclosing the said motor-coils.

On the inside of the motor-coil is placed a non-metallic protecting-tube E, which should be of a material not affected by moisture or by lubricants. Said tube being tightly joined at its ends to the heads D D' forms a most effective protection to the motor-coils.

F is a plunger of magnetic material, which is adapted to be moved back and forth under the influence of current flowing in the said motor-coils.

G is a forwardly or downwardly extending rod connected permanently at one end to the plunger F, and adapted to be provided at its outer end with a chuck g for the reception of a drill or other tool. The head D is provided with a gland d, surrounding and centering the piston-rod G. The other end of the piston F is also provided with an extension in the form of a rod H, which works through a gland d' in the head D'. The piston F, being thus guided at both ends, moves within the non-metallic tube E without coming into actual mechanical contact therewith.

In order to be able to start the piston F with equal facility in either direction, I provide counterbalancing-springs f f', which may be disposed as convenient, being shown in Fig. 1 on the interior of the cylinder, having their bearings against the ends of the piston and the iron heads of the machine. These springs being about equal in power will, when no current is flowing through the motor-coils A B, normally hold the piston F in central position with relation to said motor-coils, so that it may move under the influence of whichever coil first receives the current.

Where the engine is designed to perform

work under similar conditions at all times—as, for example, in sinking shallow holes with a light drill and in a vertical position—comparatively few difficulties are encountered, 5 and all complications may be avoided; but where, as is frequently the case, the length and consequent weight of the tools to be operated are altogether disproportionate to the weight the plunger can lift a readjustment 10 of the parts becomes desirable, and under such circumstances I keep the magnetic pull in one direction or the other by elongating the plunger F in the desired direction, and I also, in some instances, add to this effect or 15 prevent detraction therefrom by making the piston-rod G of non-magnetic metal, such as phosphor-bronze or tempered copper.

As a specific feature of the invention I claim the employment, in connection with a 20 magnetic piston, of extensions or continuations guiding the same and serving also as a magnetic continuation in either direction to be used, arranged, and employed according to the work required. Both extensions may be 25 non-magnetic and used as guides for mechanical purposes, or either one may be magnetic for electrical reasons, no limitation whatever being placed upon the employment of these extensions as and for the purposes set forth, 30 and as a means for extending the capacity of the apparatus to various different kinds of work which it would otherwise be unable to perform. Where one extension is magnetic and the other non-magnetic, the side having 35 the magnetic extension will be drawn into the solenoid most forcibly, so that with a magnetic extension toward the tool in working vertically more lifting-power is secured than where the magnetic extension is in the opposite position. In deep vertical drilling, 40 therefore, the magnetic extension would be from the lower portion of the piston, in order to compensate for the added weight of the tool as the work progresses, while in machines used for undercutting coal or to operate on any material in a horizontal position 45 the magnetic extension would be on the upper end of the piston—that is, on the end opposite the tool-holder—since in that case the 50 weight of the tool would not vary, and the object would be to strike the hardest possible blow.

In deep vertical boring, when the weight of the moving part is considerable, the magnetic extension is on the lower end of the piston, and it would be actually better to make the upper extension non-magnetic, in order to hinder the descent of the drill as little as possible and to secure the greatest 60 working effect therefrom. A very desirable construction is embodied in a piston having a magnetic extension at one end and a non-magnetic extension at the other, both being of the same size and shape, so that under varying 65 conditions the piston can be reversed and the tool attached to either end. The form seen in Fig. 2, for instance, is capable of such

use, since the tool-holder can be screwed or otherwise attached to either of the extensions G' H'. Obviously the machine may be reversed upon its bearings, if desired, instead of removing the piston and reversing it. 70

The counterbalancing-springs f f' exert a beneficial influence in the operation of the machine, for not only do they help to start 75 the piston on its return-stroke, but they aid in bringing it forward before the magnetic maximum has been attained, and this condition is advantageous, since it both increases the rapidity of the stroke and the effective 80 force of the blow by helping the piston toward the point of greatest magnetic effect, and thereby, of course, enabling the field of force to produce a stronger effect upon the piston. 85

Various methods of arranging and adjusting the springs may be employed with a like effect, and by using springs at each end the power absorbed in one direction is given off 90 in the other, and springs of different strength 95 can be used to modify the effect either forward or backward. The construction shown in Fig. 2 differs from that seen in Fig. 1 principally in the arrangement of the counterbalance-springs. The continuations G' H' 95 from the plunger F' appear to be somewhat longer than those seen in Fig. 1; but it must be understood that the magnetic part or parts of these extensions may be as long or as short as required by the diverse conditions to be 100 met. As seen in said Fig. 2, the springs f² f³ are placed upon the rods G' H' upon that portion exterior to the cylinder formed by the shell and heads of the drilling-engine. The rods G' H' are furthermore screw-threaded upon a part of their length and provided with jam-nuts f⁴ f⁵, between which and the ends of the said cylinder the springs f² f³ are held. The extremities of the rods G' H' 105 may be slotted and shouldered to receive the 110 chuck g, (seen in Fig. 1,) or a screw-threaded chuck may be employed. As here indicated, the said springs are equal in tension and adapted to produce equal effects. This, of course, applies and is the correct arrangement for conditions under which the results should always be the same—as, for example, 115 in a horizontally-acting machine. Where, however, a constantly-increasing weight of apparatus is to be moved, the spring most affected thereby may be made to preponderate 120 in power, as by the substitution of a heavier spring or by the adjustment of the tension devices here represented by the jam-nuts. A hand-wheel might, of course, be substituted 125 for the jam-nuts, and various other specific forms of adjusting mechanism may be employed without affecting the invention.

A desirable construction is indicated in Fig. 3, in which is shown a plunger F with extensions. The piston F can be made hollow, and to its upper end is secured a magnetic extension H, while its lower end is provided with a non-magnetic extension G, it being dis-

tinctly understood, however, that this arrangement is designed for special conditions only—such, for instance, as the operation of a horizontally-acting machine, as a coal-digger. As 5 before stated, where other conditions have to be met, the magnetic and non-magnetic continuations of the piston are reversed by simply turning the piston end for end, as both extensions can hold the tool, or modified in 10 accordance with the principles set forth.

In view of the fact that a piston guided as the one herein referred to cannot rotate freely in its bearing, means for imparting to the same the usual step-by-step rotary movement 15 become necessary, and this I provide by forming a vertical groove in the continuation of the piston, whether the same be magnetic or non-magnetic. A ratchet I is placed upon the grooved continuation and is provided with a 20 feather or spline i engaging the groove. The ratchet is seated upon the upper cylinder-head D', the rod G or H playing freely therethrough. Below the ratchet is seated a rotatably-moving lever J, provided with retracting-spring j, for normally holding it in retracted position. The lever J is provided with 25 pawls j' j'', arranged to engage the teeth of the ratchet, and the free ends of the said lever also carry magnetic armatures arranged in 30 position to be attracted by electro-magnetic cores k k', which may be energized from the magnetism of the said cylinder-head or by means of small field-magnet coils LL', provided 35 for the purpose and connected in circuit with one of the motor-coils. This would result in intermittently magnetizing the said cores k k', which, attracting the armatures K K upon the lever J, will impart a step-by-step movement to the ratchet and the tool.

40 As seen in Fig. 4, the engine when operated as a drill may be arranged to be fed upon a vertical support, and the support itself may be arranged in any convenient manner—as, for example, an upright or post M is secured in any convenient manner, and upon this 45 post is placed an adjustable clip m, which is provided with a friction or other clamp N. From the clamp N extends a part which forms a frame O, partially inclosing the exterior of 50 the cylinder of the engine. The frame O carries a vertically-mounted feed-screw P, which is provided with operating-gears p p' and a handle Q. Guide-rods q q' are rigidly attached to the heads of the engine and serve to guide 55 its vertical movement in the frame O under the influence of the feed-screw P. The frame O has a narrower portion adjacent to the feed-screw, and upon the edges of this portion are formed parallel vertical guiding-surfaces R. 60 The upper cylinder-head D' is provided with a cross-head r, formed to engage the guides R R and to keep the parts in desired mechanical relation while being moved by the feed-screw, and also to afford a strong durable connection capable of withstanding the jarring 65 and vibration incident to the operation of the machine.

The engine-sustaining devices may be constructed in a variety of ways, the one here shown, however, being found convenient and 70 serviceable. The friction-clamp N comprises grooved semicircular parts held together by bolts n. The clamp m terminates in a bevel-edged disk m', and a corresponding disk m'' extends from the frame O. When the two 75 disks are forced together by the action of the clamps N upon their oppositely-sloping edges, the faces of the disks are in frictional contact and a very firm and solid, though adjustable, connection is made.

80 Under some circumstances I find that a single counterbalance-spring may be used with advantage as a means of compensating for the weight of the drilling-tool, and thereby quickening the movements of the parts. Such 85 an arrangement is shown in Fig. 4, a spring f' being there indicated in position around the upper piston-extension, where it will assist the upper motor-coil in raising the drill.

Various changes and modifications may be 90 made in the apparatus herein shown and described without departing from the spirit of the invention, the specific forms shown being by way of illustration, and not for the purpose of limiting the invention thereto, since 95 the same relation of the essential element of the invention might be otherwise secured.

Having described my invention, what I claim, and desire to secure by Letters Patent, 100

1. In a reciprocating electric engine, the combination, with a motor coil or coils, of a magnetic piston adapted to be reciprocated therein, and a magnetic extension upon said piston for causing said piston to move with 105 greater force in one direction than in the other.

2. In a reciprocating electric engine, the combination, with a motor coil or coils, of a magnetic piston, a tool-holder connected 110 thereto for carrying the tool, and a magnetic extension upon said piston for imparting a preponderance of power to the stroke in one direction, substantially as described.

3. In a reciprocating electric engine, the combination, with motor-coils, of a magnetic piston adapted to be reciprocated therein, and a magnetic continuation extending from 115 one end of said piston, whereby the stroke of said piston is caused to preponderate in power 120 in one direction, substantially as described.

4. In a reciprocating electric engine, the combination, with motor-coils and a magnetic piston adapted for reciprocation therein, of an exterior casing for said coils and extensions 125 from the ends of said piston, said extensions passing through suitable bearings in the ends of the casing for guiding said piston in its movement, substantially as described.

5. In a reciprocating electric engine, the 130 combination of motor-coils, a magnet c piston adapted to reciprocate in said coils, a casing inclosing the coils and having bearings at its extremities, extensions upon the piston pass-

- ing through said bearings for guiding the piston in its movement, one of said extensions being of magnetic material and forming a magnetic extension of the piston, thereby acting 5 to produce a preponderance of power in one direction, substantially as described.
6. In a reciprocating electric engine, the combination of motor-coils, a magnetic piston adapted to be reciprocated therein, an exterior 10 shell or casing, metallic heads connected to the casing and provided with central bearings, a non-metallic lining upon the interior of the motor-coils, and guide-rods extending from the ends of the piston through the ends 15 of the casing and guiding said piston in its movement, thereby keeping the same out of contact with the non-metallic lining.
7. A reciprocating electric engine comprising a motor coil or coils, a magnetic piston 20 adapted to be reciprocated therein, an exterior shell incasing the coils and heads therefor, an extension from the piston for connection with the tool, an extension from the opposite end of the piston, and an adjustable spring 25 upon said last-named extension for modifying the action of the piston, substantially as described.
8. In a reciprocating electric engine, motor-coils and a magnetic piston adapted to be reciprocated therein, a casing inclosing said coils and piston, and counterbalancing-springs at each end of said piston, substantially as described.
9. In a reciprocating electric engine, motor-coils, a magnetic piston adapted to be reciprocated therein, an exterior casing having apertured heads, extensions from said piston passing through said heads and guided therein, and an adjustable spring or springs between the casing and piston, substantially as described.
10. In a reciprocating electric engine, motor-coils, a magnetic piston adapted to be reciprocated therein, an exterior casing having apertured heads, extensions from said piston passing through said heads and guided therein, and adjustable springs placed between the casing and the extensions of the piston, substantially as described.
11. In a reciprocating electric engine, a magnetic piston provided with an extension at each end adapted for connection to a tool-holder, one of said extensions being formed of magnetic and the other of non-magnetic material.
12. In a reciprocating electric engine, a hollow magnetic piston provided with an extension at each end adapted for connection to a
- tool-holder, one of said extensions being formed of magnetic metal, substantially as described.
13. In an electric reciprocating engine actuated by rising and falling currents, the combination, with a rotatable tool-actuating piston, of magnetic or electro-magnetic means 65 for imparting an intermittent rotary movement thereto.
14. In an electric reciprocating engine, a rotatable piston, an intermittently-energized stationary magnet, an armature therefor, and 70 detachable connections between said armature and the piston, substantially as described.
15. In an electric reciprocating engine actuated by rising and falling currents, a tool-operating piston and electro-magnetic means 75 for rotating the piston and tool, comprising an intermittently-energized electro-magnet, and a detachable connection between the piston and actuating-magnet, said detachable connection comprising a magnetic body.
16. In an electric reciprocating engine, the combination, with a motor coil or coils and suitable casing therefor, of a magnetic piston for reciprocation therein, said piston having 85 a tool-holding extension at one end and a guiding-extension at the other, a ratchet engaging the guiding-extension, an armature having pawls adapted to engage the ratchet, and an electro-magnet arranged to be energized intermittently to attract the armature and operate the ratchet, thereby imparting rotary movement to the guiding-extension, the piston, and tool-holder, substantially as described.
17. The combination, with an engine or device to be supported, said device provided with a friction-disk having a beveled edge, of a support provided with a corresponding disk, and an adjustable clamp engaging the 95 disks and forcing them together, substantially as described.
18. The combination, with an engine or device to be supported, said device provided with a friction-disk having a bevel edge, of a support provided with a corresponding disk, and an adjustable grooved clamp engaging the edges of the disks to force them into frictional contact, substantially as described.

In testimony whereof I affix my signature in presence of two witnesses.
